UNITED STATES PATENT OFFICE

HUMBERT M. FENATI, OF NEW CASTLE, PENNSYLVANIA

BRICK MACHINE

Application filed April 12, 1930. Serial No. 443,853.

My invention relates to improvements in brick making machinery, and has for its object to provide means for covering or impregnating the surfaces of the brick with a granular material as sand, during manufacture. In the modern manufacture of building units of this kind a rectangular column or bar of clay is projected or extruded horizontally through and beyond a forming die, after which it is cut or severed transversely into the individual units and carried away for further treatment, as for burning.

Various means have been utilized for applying to the surface of the advancing clay bar a covering or coating finish by application thereto of sand or the like, as by distributing such granular material over and around the bar, with pressure thereon into its surface at the point of final discharge, by action of the surrounding walls. One difficulty encountered however has been to completely cover all four sides of the column, and particularly the under side, due to absence or irregularity of any sufficiently effective pressing or regularly impregnating means.

In my invention I provide a reciprocable pusher, so constructed and arranged underneath the bar or column that it will regularly and efficiently push the body of sand forwardly and upwardly, positively bringing it into contact with the bar and insuring regular and continuous application thereto prior to emission from the surrounding casing.

One preferred embodiment of the invention is illustrated in the accompanying drawings in which:

Fig. 1 is a longitudinal vertical section of the active portion of a brick making machine, showing my invention;

Fig. 2 is a horizontal section on the line II—II of Fig. 1;

Fig. 3 is a cross section on the line III—III of Fig. 1.

In a machine of the kind involved a continuous column or bar 2 of plastic clay is forced or extruded outwardly from the discharge nozzle 3 of a brick machine, of well known construction. The bar 2 is forced forwardly through die 3 by suitable plunger mechanism, not shown, by which the clay is

closely compressed at top, bottom, and the opposite sides, the column then slightly expanding and passing finally through the terminal limiting die 4 of casing 5.

Said casing as shown extends forwardly beyond the die 3, being secured to it and the surrounding framing, as at 6, in any suitable manner. Casing 5 is sufficiently large to provide between its walls and the advancing bar 2 a surrounding receiving cavity of sand or other granular covering material as shown. Such sand is delivered downwardly to the space from any suitable receiving or storage hopper 7 by gravity, and is usually in a dry, clean condition.

Barriers or partitions 8 extend inwardly from the walls of casing 5 at top, bottom and sides, terminating closely adjacent to the surfaces of the advancing bar, thereby preventing the backward spreading of the sand toward the exit die 3. The lower barrier 8 is preferably provided with a supplemental forward extension 9, tending to further protect the bar, and also acting as a protecting coping for the actuating crank mechanism for the pusher, hereinafter described.

A conveyor belt 10 mounted on pulley 11 of shaft 12 is arranged underneath the extruded bar for support thereof in transporting it toward the severing means.

For the purposes of effecting the objects of the present invention, I provide a pusher A in the form of a reciprocable slab or plate of metal extending forwardly and upwardly over the lower wall of casing 5 and movable thereon forwardly and backwardly. Pusher A as shown is preferably of a sufficient width to extend by its rear portion at least co-extensive with the width of bar 2, and is provided with an actuating crank shaft 13.

Crank 13 is mounted by its off-set journals 14 in bearings 15 of casing 5 and is connected by partly-embracing bearing straps 16 and 17 with pusher A. Such strap connections or semi-bearings are so connected as to engage the crank in either direction of movement, leaving a portion of the crank exposed so as to avoid congestion of sand with resulting cutting or friction.

The forward portion of pusher A is ser-

100

rated by a series of tooth-like projections 18 sloping upwardly and forwardly. As shown, the opposite sides are preferably in duplicate formation, allowing for reversal of the 5 pusher in case of wear.

Such projections also slope forwardly and outwardly at the front from the longitudinal center of the pusher as shown in Fig. 2, thereby tending to converge the sand from 10

10 each side constantly toward the middle portion of the bar. The length of the projections also decrease inwardly at each side toward the front, and the oppositely inclined series are serrated or toothed at their side 15 terminals as at 19, thereby tending to continuously and positively engage the sand at each forward movement.

The crank 13 is alternately actuated by means of a terminal lever 20 and connecting 20 rod 21 of crank disk 22.

The latter is geared in any suitable manner, as by pinion 23 and gear 24, with the driving or driven shaft 12 of pulley 11, as clearly shown in Fig. 1.

25 As thus constructed the pusher A will be actuated during operation of the machine, forcing the sand constantly and continuously upwardly and forwardly against the under side of the bar, the entire upper portion being surrounded by the copious sand supply 30 discharged from the hopper 7.

By such action the entire four surfaces of the bar 2 are positively supplied with sand which is then pressed into its surfaces by the 35 terminal 4 of the casing as the bar emerges. Thereafter, upon severing the bar into individual units or bricks, the edges of the resulting brick which are ordinarily exposed in a building, are completely covered with the 40 sand which becomes fixedly attached by the burning operation in the kiln.

The construction and operation of the invention will be readily understood from the foregoing description, and it may be utilized 45 in connection with the formation of bars of plastic material, as clay, either in the manufacture of bricks or similar units, or as otherwise adapted.

The invention may be changed or modified by the skilled mechanic in various features or detail construction to adapt it to special conditions, but all such changes are to be understood as within the scope of the following claims.

55 What I claim is:

1. In a brick machine having an extruding die and a surrounding casing in advance thereof, a reciprocable pusher within the casing and below the path of an extruded product.

60 2. In a brick machine having an extruding die and a surrounding sand casing in advance thereof, a reciprocable pusher operable below the path of an extruded product having a series of pushing teeth.

3. In a brick machine having an extruding die and a surrounding sand casing in advance thereof, a reciprocable pusher operable below the path of an extruded product in an alternating forwardly and upwardly direction.

70 4. In a brick machine, the combination with an extruding die and a sand casing, of a reciprocable pusher longitudinally movable along the wall of the casing.

75 5. In a brick machine, the combination with an extruding die and a sand casing having a lower inclined wall, of a reciprocable pusher longitudinally movable along the lower wall of the casing.

80 6. In a brick machine, the combination with an extruding die and a sand casing having a lower inclined wall, of a reciprocable pusher longitudinally movable along the lower wall of the casing provided with outwardly diverging edges.

85 7. In a brick machine, the combination with an extruding die and a sand casing having a lower inclined wall, of a reciprocable pusher longitudinally movable along the lower wall of the casing provided with a series of pushing edges.

90 8. In a brick machine, the combination with an extruding die and a sand casing having a lower inclined wall, of a reciprocable pusher longitudinally movable along the lower wall of the casing provided with opposite inwardly inclined series of sand engaging projections.

95 9. In a brick machine, the combination with an extruding die and a sand casing having a lower inclined wall, of a reciprocable pusher longitudinally movable along the lower wall of the casing provided with inwardly converging front edges, an upper shouldered face, and forwardly and inwardly disposed toothed edges.

100 10. In a brick machine, the combination with an extruding die and a sand casing having a lower inclined wall, of a reciprocable pusher longitudinally movable along the lower wall of the casing, means for actuating the pusher, and protecting walls surrounding the extruding die rearwardly of the pusher.

115 11. In combination, an extruding die having a sand enclosing casing in advance thereof provided with an exit opening, a reciprocable pusher supported on the lower wall of the casing, a transversely arranged actuating crank engaging the pusher, and means for imparting movement to the crank.

120 12. In combination, an extruding die having a sand enclosing casing in advance thereof provided with an exit opening, a reciprocable pusher supported on the lower wall of the casing, a transversely arranged actuating crank engaging the pusher a bar supporting belt and driving means therefor, and means connected therewith for imparting movement to the crank.

13. A sand pusher for brick making machines consisting of a flat slab or plate having a series of oppositely disposed inwardly converging pushing shoulders increasing in length backwardly and terminating in pushing points with intervening V-shaped spaces along its opposite edges.

14. A sand pusher for brick making machines consisting of a flat slab or plate having a series of oppositely disposed inwardly converging pushing shoulders increasing in length backwardly and terminating in pushing points with intervening V-shaped spaces along its opposite edges, and provided at its rear edge with a plurality of crank engaging bearings.

In testimony whereof I hereunto affix my signature.

HUMBERT M. FENATI.
